FOREIGN PATENT DOCUMENTS

EP 3123893 A1 * 2/2017

Primary Examiner — Richard E Chilcot(74) *Attorney, Agent, or Firm* — Sughrue Mion, PLLC(57) **CLAIM**

The ornamental design for a suitcase, as shown and described.

DESCRIPTION

FIG. 3.1 is a perspective view of the suitcase according to the invention;

FIG. 3.2 is a front view thereof;

FIG. 3.3 is a back view thereof;

FIG. 3.4 is a right side view thereof;

FIG. 3.5 is a left side view thereof;

FIG. 3.6 is a top view thereof;

FIG. 3.7 is a bottom view thereof;

FIG. 3.8 is a front view thereof with section lines;

FIG. 3.9 is a partial sectional view thereof;

FIG. 3.10 is a partial sectional view thereof;

FIG. 3.11 is a back view thereof with section lines;

FIG. 3.12 is a partial sectional view thereof; and

FIG. 3.13 is a partial sectional view thereof.

(Continued)

The broken lines are used to show portions of the suitcase that are not being claimed, and thus form no part of the claimed design.

1 Claim, 13 Drawing Sheets
